UNITED STATES PATENT OFFICE.

WILLIAM G. AYRES AND SETH L. COLE, OF BROOKLYN, NEW YORK.

IMPROVED CIGAR-MACHINE.

Specification forming part of Letters Patent No. **99,745**, dated February 15, 1870; antedated February 9, 1870.

To all whom it may concern:

Be it known that we, WILLIAM G. AYRES and SETH L. COLE, of the city of Brooklyn, in the county of Kings and State of New York, have invented certain new and useful Improvements in Machinery for Making and Finishing Cigars by the Application of Flexible Non-Adhesive Rollers; and we hereby declare the following to be a full, clear, and exact description thereof, reference being had to the accompanying drawings, which are lettered to correspond with and form a part of the specification.

To enable the public to understand the nature of our said invention, and those who are skilled in the mechanic arts to construct and operate the same, we will describe it as follows, to wit:

Figure 1 is a perspective drawing of our machine for making and finishing cigars. A is a horizontal shaft, which passes through one end of the lever I, that being secured in its place by means of a small set-screw, wedge, or key, u.

The lever I is employed to raise the roller C by means of the connecting-arms B and B', the front ends of which constitute and form the bearings of the horizontal axes of the cork roller C, so that when the lever I is depressed by the action of a foot-lever or other suitable power the said roller C is raised and thrown out of gear to enable the operator to feed and remove the cigar from the machine in a finished state. D is a roller, similar in form to the roller C, and with it performs the operation of shaping the cigar and winding the wrapper around the same in a spiral or volute form until it reaches the cone-shaped end or apex of the cigar, which is cut off by the revolving cutters F and L.

The knife F is secured to a sleeve, G, Fig. 2, around the end of the axis of the cork roller C, or otherwise arranged to produce a rotary shear cut with the knife L, which is secured to and forms a part of the end of the roller D. The adjustable knife F may be operated with a separate gearing from roller C, if thought best, the effect of which would be the same.

M is the table, upon which the operator guides the prepared wrapper during the process of winding. The edge V (of the table) next the machine is fashioned to correspond with the form of the cigar, and serves the double purpose of keeping the cigar in its proper place, at the same time smoothing the wrapper.

K K' K" K'" are the gearing-wheels. K receives its motion from the pulley P, and imparts the same to the connecting-gearing K' K" K''. The frame-work S S S is strengthened and supported by connecting horizontal rods H H, and is provided with curved slots N N, for the purpose of receiving the ends of the axes of the roller C, and allow the same to be moved up or down by the lever I, for the ostensible purpose set forth. The horizontal shaft or bar A serves as a fulcrum for the lever I.

Fig. 2 is a front elevation of our machine, having the table removed in order to show more clearly the forming cork rollers C D and independent back roller, O, also the revolving knives F and L at the ends of the cork formers C and D. The roller C is raised in the curved slots N N, Fig. 1, to show more clearly the different parts of the apparatus.

We are aware that cigar-machines have heretofore been constructed with rollers and cutters combined; but we are not aware that the curved edge of the table has ever been used in place of a fourth roller. Therefore

What we do claim as new and of our invention in the machine as above described is—

The combination of the table M, having the edge V, shaped as described, with the slotted frame S S and rollers C, D, and O, as and for the purpose described.

In testimony whereof we hereunto subscribe our names in the presence of two witnesses.

WM. G. AYRES.
SETH L. COLE.
